UNITED STATES PATENT OFFICE.

MIHALY JENEY AND PAUL ORBAN, OF NEW YORK, N. Y.

AUTOMATIC RAILROAD SAFETY-SIGNAL DEVICE.

Application filed December 21, 1926. Serial No. 156,096.

This invention relates generally to rail-ways, and has more particular reference to a novel type of automatic signal therefor.

The invention has for an object the pro-
5 vision of an improved signal which will act positively and efficiently, and which can be manufactured and sold at a reasonable cost.

For further comprehension of the invention and of the objects and advantages 10 thereof, reference will be had to the following description and accompanying drawing, and to the appended claims in which the various novel features of the invention are more particularly set forth.

15 Referring to the drawing forming a material part of this disclosure:

Fig. 1 is a fragmentary plan view of rail-way tracks, with rail contact trucks thereon.

Fig. 2 is a side elevational view of the 20 tracks with a locomotive thereon, and one rail contact truck attached to the locomotive.

Fig. 3 is a fragmentary enlarged side view 25 of a rail contact truck used in this invention.

Fig. 4 is a plan view thereof.

Fig. 5 is a horizontal sectional view of an 30 apparatus box with certain apparatus used in this invention, taken on the line 5—5 of Fig. 6.

Fig. 6 is a vertical sectional view taken on the line 6—6 of Fig. 5.

Fig. 7 is a vertical sectional view taken 35 on the line 7—7 of Fig. 6.

Fig. 8 is a vertical sectional view taken 40 on the line 8—8 of Fig. 5.

Fig. 9 is a schematic wiring diagram of 45 the invention device.

Fig. 10 is an enlarged fragmentary sec- 50 tional view of Fig. 2.

The reference numerals 10, 11, indicate 55 generally rails of a track, separated by spaces 12, these spaces being so arranged that the spaces of rail 10 coincide with the center of a rail 11, and the spaces 12 of rail 11 coincide with the center of a rail 45—10.

The locomotive 13 on the rails 10, 11 has coupled thereto as at 14 a rail-contact truck formed of a frame 15 supporting a pair of axles 16 supporting wheels 17 resting on the 50 rails 10, 11, and insulated from the frame 15 by insulations 18. The shafts 16 are formed by insulations 19 intermediate of their ends, electrically separating the wheels on the shaft ends. Mounted on the shafts 16

are collars 20 engageable by contact arms 21, 55 22 supported from the frame 15 by terminals 23, 24, 25, and 26. A bent arm 27 is pivoted at 28 to frame 15, and the ends thereof project under contact arms 22. Attached to the center of the bent arm 27 is a 60 connecting rod 29 secured at its upper end to one arm of a bell crank 30 pivoted at 31 in the cab of the locomotive 13, and adjacent a fixed serrated segment 32 engageable by a rod 33 slidable along the free arm 65 of bell crank 30, and operated by hand lever 34. In Fig. 1, a plan view of the rail contact truck of locomotive 13 is shown at 35, and a plan view of another rail contact truck of a locomotive not shown on the 70 drawing is shown at 36.

Within the cab of the locomotive 13 is an apparatus box 37 having a glass front 38. A red lamp 39, a green lamp 40, an electric bell 41, fuses 42, a solenoid 43, and a switch 75 base 44 are mounted within the box 37. Pivoted at their upper ends to the base 44 are contact arms 45, 46, 47, 48 connected intermediate of their ends to bar 49 slidably mounted and formed at one end with a hook 50 engageable by hook 51 pivoted at 52 to the box, and attached at 53 to the solenoid armature, while spring 54 normally urges the hooks into engagement with each other. When the hooks 50, 51 are engaged, the contact arms 45, 46, 47, 48 are 80 disengaged from contacts 55, 56, 57, 58 respectively, while spring 59 normally tries to urge the arms into engagement with the coating contacts. Projecting from the bar 90 49 is a rod 60 with a handle 61 on its end.

Also mounted in the box 37 is an electric motor 62 having on its shaft a worm 63 meshing with a worm wheel 64 rotatively arranged in casing 65 connected to the body of the motor as by web 66. Mounted on the shaft 65 is a wheel 67 having on each side a metal contact plate 68 with a half segment strip 69 added along its edge. Connected to box 37 and resting against the faces of the 100 wheel 67 are contact arms 70, 71, 72, 73 connected by wires 74 to certain terminals.

In certain regions of the tracks, such as where the tracks enter a tunnel, or at curves and places where large stretches of the track 105 are not visible, zones are formed in which each of the individual parts of the rails 10 and 11 are connected to adjacent parts by

wires 75 which are provided with sources of power, such as batteries 76. Terminals 23 and 25 are electrically connected, as are terminals 24, 26, and a lead 77 from terminals 23, 25 connects with one end of the solenoid 43, and the other end of solenoid 43 connects by lead 78 to terminals 24, 26. In another locomotive not shown on the drawing, leads 77' and 78' from its rail contact truck, connect with its solenoid 43. If the locomotives enter a track region having a zone arrangement, an electric current will flow, as specifically shown in Fig. 9, from, for example, the source of power 76^a to rail 11^a, lead 78, solenoid 43 on the first locomotive, lead 77, rail 10^a, lead 77', the solenoid of the second locomotive, not shown on the drawing, and back through lead 78' to the power source 76^a. The solenoid on each locomotive will be energized, causing hook 51 to move upwards against the action of spring 54, releasing hook 50, allowing rod 49 to be moved by spring 59 so that the contact arms 45, 46, 47, 48 engage contact arms 55, 56, 57, 58.

The closing of contacts 48, 58 causes motor 62 to operate, turning wheel 67. Contact arms 72 and 73 may be connected, and contact arms 70 and 71 may, likewise, be connected. Contacts 70, 71 contact with 68, while 72 and 73 are on the edge of the wheel only, see Fig. 7, so that they contact only with 69, as the wheel turns and 69 passes beneath these contacts. The leads 80, 81 connect contacts 70, 71 and 72, 73 in series with bell 41, operable by the closing of contacts 46, 56. The closing of contacts 45 and 55, and 47 and 57 results in lighting lamps 39, 40. A source of power for lighting the lamps 39, 40 and operating the bell 41 is indicated at 82, and for the motor 62 another source is indicated at 83. The burning lights and the intermittently ringing bell warns the locomotive drivers that another train is in the same zone. Lamp 39 is red, and 40 green, and flashing these lamps serves to attract attention more rapidly than if both lights were of the same color, since the amount of difference is a function in the rapidity of attracting attention.

As the wheels 17 of the contact trucks turn necessarily, the collars 20 also turn, wearing out the contact arms 21, 22, which must therefore be replaced from time to time. Operating handle 34 on bell crank 30, moves rod 33 free from the serrations 32, permitting the moving of the bell crank 30, which motion is communicated to rod 29 and hence to bent rod 27. Pushing 30 in one direction causes the ends of bent rod 27 to lift the contact arms 22 free from the collars. When arms 21 become worn, arms 22 may be re-engaged by the proper manipulation of bell crank 30.

65 A slot 84 in member 38 permits the rod

60 to slide as directed by bar 49. Moving handle 61 to the right, the hooks 50, 51 may be re-engaged.

While we have illustrated and described our invention with some degree of particularity, we realize that in practice various alterations therein may be made. We therefore reserve the right and privilege of changing the details of construction or otherwise altering the arrangement of the correlated parts without departing from the spirit or the scope of the appended claims.

Having thus described our invention what we claim as new and desire to secure by United States Letters Patent is:

1. In combination with a railway track provided with zones, a signal device on locomotives, and means for operating the signal device when two locomotives enter the same zone, said means comprising a solenoid connected with a hook engageable with a second hook on a rod, connected with switches controlling circuits including a source of power, and a motor driven wheel equipped with contact discs electrically connected to certain parts of the signal device.

2. In combination with a locomotive and a rail contact truck, a frame for the rail contact truck, contact arms secured to the frame, a bent rod pivoted to the frame, and having its ends engaged beneath certain of the contact arms, a connecting rod attached to the bent rod, a bell crank pivoted to the locomotive, the free end of the connecting rod being attached to one arm of the bell crank, a rod slideable on the other arm of the bell crank, a handle on the upper end of the rod, and a serrated segment attached to the locomotive, the bottom end of the rod being engageable in the serrated segment.

3. In combination with a locomotive and a rail contact track, a frame for the rail contact truck, contact arms secured to the frame, leads connected with said contact arms, a solenoid operated signal device in said locomotive, and said leads being connected with said solenoid, a bent rod pivoted to the frame, and having its ends engaged beneath certain of the contact arms, a connecting rod attached to the bent rod, a bell crank pivoted to the locomotive, the free end of the connecting rod being attached to one arm of the bell crank, a rod slideable on the other arm of the bell crank, a handle on the upper end of the rod, and a serrated segment attached to the locomotive, the bottom end of the rod being engageable in the serrated segment.

4. The combination with a locomotive having an automatic signal device for detecting when another similarly equipped locomotive enters the same rail zone, of a frame connected with the locomotive, a rail contact truck attached thereto, contact arms secured to the frame, leads connected with said contact arms and with said automatic

signal device, a bent rod pivoted to the frame, and having its ends engaged beneath certain of the contact arms, a connecting rod attached to the bent rod, a bell crank pivoted to the locomotive, the free end of the connecting rod being attached to one arm of the bell crank, a rod slidable on the other arm of the bell crank, a handle on the upper end

of the rod, and a serrated segment attached to the locomotive, the bottom end of the rod being engageable in the serrated segment.

In testimony whereof we have affixed our signatures.

MIHALY JENEY.
PAUL ORBAN.
